(57) **CLAIM**

The ornamental design for a fastening latch, as shown and described.

DESCRIPTION

FIG. 1 is a top, front, right side perspective view of a fastening latch with the latch in a vertical position;
FIG. 2 is a top, front, right side perspective view of a fastening latch with the latch in a forward position;
FIG. 3 is a top, front, right side perspective view of a fastening latch with the latch in a rearward position;
FIG. 4 is a front elevation view of a fastening latch with the latch in a vertical position;
FIG. 5 is a back elevation view thereof;
FIG. 6 is a left side elevation view thereof;
FIG. 7 is a right side elevation view thereof;
FIG. 8 is a top plan view thereof; and,
FIG. 9 is a bottom plan view thereof.
The broken lines in FIGS. 1-9 illustrate portions of the fastening latch that form no part of the claimed design.
